UNITED STATES PATENT OFFICE.

FAY O. FARWELL, OF DUBUQUE, IOWA.

MULTIPLE-ARM REPRODUCER MECHANISM.

1,371,614.

Specification of Letters Patent. Patented Mar. 15, 1921.

Application filed February 11, 1918. Serial No. 216,450.

To all whom it may concern:

Be it known that I, FAY O. FARWELL, a citizen of the United States, and a resident of the city of Dubuque, in the county of

5 Dubuque and State of Iowa, have invented certain new and useful Improvements in Multiple-Arm Reproducer Mechanism; and I do hereby declare that the following is a full, clear, and exact description of the same, 10 reference being had to the accompanying drawings and to the numerals of reference marked thereon, which form a part of this specification.

In the usual construction of phonographs, 15 it has been the practice to provide but a single reproducer arm which is rotatably mounted at one end and has a needle carrying sound box secured to the other end thereof.

20 This invention, however, pertains to an improved form of a phonograph reproducing mechanism in which a plurality of adjustable reproducing arms are provided attached to a single support rotatably mounted 25 on the phonograph cabinet, whereby said arms may be simultaneously rotated to permit the playing needles thereof to simultaneously engage in the same groove of a record to permit the diaphragm associated 30 with each needle to transmit a recorded tone wave to an independent megaphone to produce an apparently single tone of increased carrying power and volume.

It is an object of this invention to produce 35 a phonograph provided with a plurality of simultaneously rotatable, adjustable reproducing means.

It is also an object of the invention to produce a multiple arm reproducer mechanism 40 provided with sound reproducing means disposed to receive and transmit both vertical and horizontal sound waves of different types of records.

Another object of this invention is the 45 construction of a phonograph equipped with a plurality of reproducer arms adapted to rotate at the same time and each arm provided with a separate stylus and connected with a separate horn.

50 It is also an object of this invention to provide a rotatable reproducer mechanism comprising a rotatable mounting having a plurality of sound reproducing arms rotatably attached thereto, and equipped with 55 sound reproducing means disposed at an angle with respect to each other, affording

a reproducer mechanism, wherein the diaphragms are sensitive to both vertical and horizontal sound waves of different types of records. 60

It is a further object of the invention to construct a phonograph equipped with a rotatable support for carrying a plurality of adjustable reproducing means, disposed at an angle with respect to each other, and 65 adapted to be rotated simultaneously with said support, and engage in practically the same point of a groove of any of the standard types of records to apparently produce a single tone of increased volume and carrying power. 70

It is an important object of this invention to construct an improved form of reproducing mechanism of simple and effective construction, and having a plurality of sound 75 reproducing means simultaneously rotatable and each provided with an independent stylus, sound box, and horn.

Other and further important objects of this invention will be apparent from the disclosures in the specification and drawings. 80

The invention (in a preferred form) is illustrated in the drawings and hereinafter more fully described.

In the drawings: 85
Figure 1 is a top plan view of a double arm reproducer mechanism embodying the principles of this invention.

Fig. 2 is an enlarged side elevation thereof. 90

Fig. 3 is an enlarged section on line 3—8 of Fig. 1 with parts in elevation.

Fig. 4 is a section taken on line 4—4 Fig. 3. 95

Fig. 5 is a sectional view taken on line 5—5 of Fig. 1.

Fig. 6 is an enlarged sectional detail taken on line 6—6 of Fig. 1.

Fig. 7 is a fragmentary section with parts in elevation, taken on line 7—7 of Fig. 6. 100

Fig. 8 is a fragmentary front elevation of a phonograph cabinet.

Fig. 9 is a side view thereof, partly broken away to show the horn construction.

Fig. 10 is a view similar to that shown in Fig. 5, of a modified form of the device. 105

As shown on the drawings:
The reference numeral 1, indicates a phonograph casing or cabinet of any desired design or form, provided with a horn chamber 2, in which horns or megaphones 3 and 4, respectively, are disposed with the enlarged 110

open ends or flaring mouth pieces thereof positioned adjacent one another flush with the front surface of the cabinet 1, while the rear restricted ends of said horns curve upwardly and are secured to the top board of said cabinet with the openings therein communicating through suitable openings in said top board. Rotatably mounted upon the cabinet 1, is a record carrying disk or table 5, for rotatably carrying a record 6, to be played.

Mounted upon the top board of the cabinet 1, to the outside of the record carrying table 5, is a circular base plate, bearing plate 15 or socket 7, having segment shaped openings 8 and 9, therein, separated by a diametrically disposed cross piece 10, integral with said socket 7. Said socket is mounted with the openings 8 and 9, thereof, registering with the openings in the cabinet top board and with the inner open ends of the horns 3 and 4, respectively. Rotatably seated in the socket 7, is a circular plate 11, having integrally formed or rigidly secured thereon a standard or support 12, provided with an integral partition wall 13, which divides the support into two passaged parts, each of which is provided with a seat 14.

Secured in each of the passaged parts of 30 the support 12, is the inner or lower end of an elbow 15, the upper end of which is horizontally disposed and has rigidly secured therein one end of a tone arm, reproducer arm or connecting sleeve 16. Adjustably 35 disposed in the other or outer end of each of the tone arms 16, is the inner end of a connecting tube, tone arm or sound tube 17, having integrally formed thereon a ball 18, provided with a small indent at the bottom 40 thereof to receive the inner end of an adjustable set screw 19, one of which projects upwardly through the bottom of each of the respective tone arms 16, as clearly shown in Fig. 7, thereby affording an adjustable pivotal support for each of said sound tubes 17. To prevent a lateral swinging movement of 45 the sound tubes 17, with respect to the arms 16, one end of a resilient metal brace rod or strap spring 21, is secured to the lower portion 50 of each of the balls 18. Each strap 21, projects into one of the arms 16, and has the inner end thereof bent upwardly to normally contact a cross rod on shaft 42, diametrically projecting through the arm 16. 55 The shaft 42, has integrally formed on one end, thereof a crank or handle 43, to permit rotation of the shaft 42. Secured on the shaft 42, is a grooved cam or finger 44, which rests upon the inner end of the strap 21, with 60 the groove thereof engaged on said strap to hold the sound tube against a lateral swinging movement.

Rigidly secured centrally on the upper inner end of each of the sound tubes 17, is 65 one end of an angled or V-cross sectioned

lever or projection 22, which extends into the respective arm 16, with the ridge directed upwardly. Each of the arms 16, is provided with an aperture 23, centrally in the top thereof and near the outer end. A 70 clamp 24, is engaged around each arm and has an upwardly directed lug 25, integrally formed at each end thereof disposed on opposite sides of the aperture 23, to afford a means for pivotally supporting an actuating member comprising an upwardly projecting integral handle or finger 27, and an integral foot or lever 28, which projects through the aperture 23, and has a V-shaped groove 29, formed in the rounded toe thereof. 75 Integrally formed on one of the lugs 25, of each of said clamps 24, is a stop 30, for limiting the upward movement of the lever 28, which is normally swung upwardly by the weight of the handle 27. The clamps 24, are prevented from sliding on the arms 16, by retaining screws 31.

Each of the sound tubes 17, has a sound box 32, mounted on the outer end thereof and disposed at an angle of approximately 90 forty-five degrees with respect to the top of the record 6. A stylus 33, provided with a removable needle or stylus point 34, is mounted upon each sound box. As clearly 95 shown in Fig. 3, the cross piece 10, is provided with a sleeve 35, through which projects a bolt 36, which threads into the partition wall 13. Mounted on said bolt between the bolt head and the sleeve 35, is a spring 37, which holds the support 12, and 100 the plate 11, thereof, seated in position.

In the modified form of the device shown in Fig. 10, the construction is practically the same as that already described except that the sound tubes 17, are replaced by 105 sound tubes 38, each having a sound box 39, secured thereto, in a plane parallel to the record 6. Each sound box is provided with a stylus 40, and a removable needle or stylus point 41. The inner ends of the tubes 110 38, are constructed the same as the tubes 17.

The operation is as follows:

As described, the phonograph is equipped with a plurality of reproducer-arms, all of 115 which are secured to a single spring controlled support rotatably mounted upon the top of the cabinet 1, in a socket plate 7. As shown in the drawings, two reproducer arms are disclosed, but it will be understood that any convenient number of arms may be provided. The arms 16, are so disposed that when in playing position, the needles 34, supported by the stylus 33, are closely associated with one another to permit the same to engage the same groove of a record 125 at the same time, whereby a plurality of similar tones are transmitted through the sound boxes and the reproducer arms to the respective horns 3 and 4, to apparently produce but a single tone of increased volume 130

and carrying power. As clearly shown in Fig. 5, it will be noted that the sound boxes 32, are disposed at right angles to one another; and at an angle of forty-five degrees to the plane of the record 6. This arrangement of the sound boxes permits the sound tubes 17, to be brought close together and positions the sound box diaphragms so that they are sensitive to both the vertical 10 and horizontal sound waves of the various types of records. By simply placing a stylus needle of the type of record to be played, in position in the stylus, the reproducer mechanism is made universal and capable 15 of playing any type of record.

While a record is being played, the needles 34, all track in the same groove of the record and as the needles advance across the record, the reproducer arms are simultaneously 20 swung toward the center of the record, causing a rotation of the arm supporting member 11—12, in the socket plate 7. The sound waves reproduced by the diaphragms of the sound boxes are transmitted 25 through the respective sound tubes, reproducer arms, through the support 11—12, and through the respective cabinet openings 8 and 9, to the horns 3 and 4, respectively. The openings 8 and 9, are so shaped that 30 during the playing of a record, the lower open ends of the sleeves 15, do not pass out of register with said openings, the lengths of which are proportional to the arc through which the reproducer arms swing 35 during the playing of a record.

As shown in Fig. 7, the sound tube is in lowered or playing position, and the lever 28, is in raised position, due to the weight of the handle 27, which forces the lever up 40 against the stop 30. When the playing of a record has been finished, the needles 34, are raised out of playing engagement with the record 6, by lifting both of the handles 27, at the same time, thus swinging the 45 levers 28, downwardly, so that the grooves 29, thereof, engage over the angle levers 22, and depress the same, thereby causing the sound tubes to pivotally swing upwardly. The weight of the handles 27, being swung 50 to the rear of the pivot point of the sound tube raising mechanism, the sound tubes and the respective needles 34, thereof, are held in an elevated position. The strap springs 21, of course, act to prevent lateral 55 swinging of the sound tubes. Some types of records, such as the Pathé require the entire weight of the reproducer to hold the playing needles in proper playing contact with the record while other types of records such 60 as the Edison require a light contact of the playing needles in the record grooves. To vary the weight of the reproducer mechanism upon the record, the cranks 43, are operated to move the fingers 44, down-

wardly against the strap springs 21, to force 65 the same downwardly, as shown in dotted lines in Fig. 7, thus causing the springs to exert a lifting tendency on the reproducer mechanisms. When playing records where the full weight of the reproducer is required 70 the springs are not depressed but contact the shafts 42.

It will of course, be understood that the sound boxes used may be disposed at any desired angle with respect to the record being played or in a plane parallel thereto, and that said sound boxes may be of different sizes with diaphragms of different thicknesses. Any convenient number of reproducing arms may be used, although only 80 two are shown. The important feature of this invention is the construction of a multitone universal reproducing mechanism adapted to play various types of records, and wherein a plurality of reproducing 85 arms are used, each provided with its own needle, stylus, sound tube and horn, but all mounted to permit simultaneous rotation thereof about a common axis. The needles of said reproducer arms are all closely associated with one another in approximately 90 the same part of the same groove of a record to be played, to produce a multitone sounding apparently like a single tone, possessing the qualities of increased volume and carrying power. 95

I am aware that numerous details of construction may be varied through a wide range without departing from the principles of this invention, and I therefore do not purpose limiting the patent granted otherwise than necessitated by the prior art. 100

I claim as my invention:

1. The combination with a rotatably mounted apertured tone arm, of a connecting tube adjustably mounted therein, an angled extension thereon extending into said arm, and means pivotally mounted on said arm and projecting through the aperture therein adapted when actuated to contact 110 said extension to elevate said reproducing means out of playing position.

2. The combination with a tone arm having an aperture therein, of a connecting tube adjustably mounted therein, resilient means 115 in said arm connected with said connecting tube to hold said connecting tube against swinging laterally, an extension on said connecting tube extending into said arm below the aperture, and grooved means pivotally mounted on said arm and extending through said aperture adapted when actuated to contact said extension to cause elevation of said connecting tube out of playing position. 120

3. A tone arm having an opening in the top thereof, means adjustably mounted thereon, and means pivotally mounted on said arm and projecting through said open-

ing adapted to contact said first mentioned means to elevate the same out of playing position.

4. The combination with a tone arm, of a connecting tube engaged therein, a reproducing mechanism supported by said tube, and cam actuated means within said arm for varying the pressure of said reproducing mechanism upon a record to be played.

10 5. The combination with a tone arm, of a tube engaged therein, resilient means secured at one end to said tube and projecting into said arm, and a cam in said arm for adjustably engaging the free end of said resilient

15 means for regulating the pressure exerted by the sound tube upon a record being played.

6. The combination with a tone arm, of a sound tube engaged therein, a resilient member secured to said sound tube and projecting into said arm, a cam member engaged with said resilient member, and means on said arm for actuating said cam member to adjust the resilient member for regulating the pressure exerted by said sound tube.

20 25 7. The combination with a tone arm, of a sound tube adjustably engaged therein, a

resilient member secured to said sound tube and projecting into said arm, a shaft projecting transversely through said arm, a cam member secured thereon and engaged with said resilient member, and a handle on said shaft to the outside of said arm to permit rotation of said cam member and adjustment of said sound tube to vary the pressure exerted thereby upon a record being played. 30 35

8. The combination with a tone arm having an opening therein, of a sound tube adjustably engaged therein, a projection secured to said sound tube and projecting into said arm, and means mounted on the exterior 40 of said arm and projecting through said opening adapted to be actuated to engage said projection to cause elevation of said arm.

In testimony whereof I have hereunto subscribed my name in the presence of two subscribing witnesses.

FAY O. FARWELL.
